No. 707,337.

Patented Aug. 19, 1902.

J. H. KOCH.

VALVE.

(Application filed Aug. 5, 1901.)

(No Model.)

UNITED STATES PATENT OFFICE.

JOHN HENRY KOCH, OF SCRANTON, PENNSYLVANIA.

VALVE.

SPECIFICATION forming part of Letters Patent No. 707,337, dated August 19, 1902.

Application filed August 5, 1901. Serial No. 70,991. (No model.)

To all whom it may concern:

Be it known that I, JOHN HENRY KOCH, a citizen of the United States, residing at Scranton, in the county of Lackawanna and State 5 of Pennsylvania, have invented certain new and useful Improvements in Valves; and I do hereby declare the following to be a full, clear, and exact description of the invention, such as will enable others skilled in the art to which 10 it appertains to make and use the same.

This invention relates to improvements in valves, and particularly to tank-valves which are adapted to be opened or closed in accordance with the height of the liquid in a tank. 15 It consists in a valve having a suitable casing and formed with a countersunk valve-seat, a valve-plunger adapted to be forced against said seat, and levers and links connecting said plunger with a float mechanism, 20 so that the valve will be controlled by the height of the liquid in the tank in which the valve is used.

It further consists in certain other novel constructions, combinations, and arrangements of parts, as will be hereinafter more fully described and claimed.

In the accompanying drawings, Figure 1 represents a vertical section through a portion of a tank, a valve being shown located 30 therein in side elevation. Fig. 2 is a vertical central section through the valve and its casing, the valve-plunger being shown seated. Fig. 3 is a similar detail sectional view, but showing the valve raised from its seat.

35 The valve forming the subject-matter of the present invention is so designed that it may be easily taken apart for repairing or for other purposes and yet is so made that it is exceedingly effective for automatically regulating 40 the inflow of water or other liquids to a tank or other similar receptacle. The valve is constructed with a divisible casing made up of a nozzle portion 1 and a valve-seat portion 2. The valve-seat portion 2 is formed with a reduced screw-threaded end 3, adapted to be 45 snugly screwed into the nozzle portion 1. The seat portion 2 is also provided with a flange, as 4, which rests against the inner surface of the tank or other receptacle in which the valve 50 is mounted. This seat portion is made sufficiently long to project through the bottom of a tank and is screw-threaded on its periph-

ery for receiving a nut 5, which may be screwed thereon tightly against the bottom of the tank for tightly drawing the seated portion in its position and forming a liquid-tight joint at this point. The seated portion is formed with a bore of suitable size, which is somewhat contracted at 6, just below the valve-seat 7. The valve-seat 7 is formed by 60 making a countersunk recess in the upper end of the seat portion 2 of the valve-casing, as clearly illustrated in Figs. 2 and 3 of the drawings. The nozzle portion 1 of the casing is provided with a cap 8, which is formed 65 with a screw-threaded portion adapted to be tightly screwed into an aperture 9, formed in the top of the nozzle member of the valve. A suitable packing-gasket, as 10, is interposed between the cap 8 and said nozzle 70 portion 1 for forming a tight joint. The cap portion 8 is formed with a central bore, as 11, within which fits snugly a valve-plunger 12. The valve-plunger 12 projects well into the nozzle member 1 of the valve and extends to 75 a point within suitable proximity to the valve-seat 7. A washer of leather or other yielding or flexible material, as 13, is secured upon the end of the valve 12 by means of an interiorly-screw-threaded cap or ring, as 14, which 80 screws upon threads formed upon the plunger 12 near its end. The upper end of the plunger projects from the cap 8 and is provided with an elongated slot 15, forming a bearing for a lever 16, which passes through 85 the same. The lever 16 is fulcrumed upon a standard 17, carried by the cap 8, the said lever being pivoted thereto at its outer end, as at 18. The lever where it passes through the slot 13 in the plunger is formed with a 90 downwardly-projecting bearing, as 19, which engages a bearing-surface within the said slot for forcing the valve-plunger downwardly. The cap 8 also carries a second standard, as 20, which is slotted to accommodate the lever 95 16 in its movement, and to the upper end of the standard 20 is pivoted a lever 21, which projects each way from its fulcrum-point, one end being comparatively short and connected by means of a link 22 with the free end of the 100 lever 16. The other end of the lever 21 receives a float-rod, as 23, made of considerable length and carrying at its end a buoyant float, as 24, of any suitable construction.

When the above valve mechanism is arranged in a tank and water or other liquid which it may contain is run out of the tank, the float 24 will of course be lowered therein 5 and the lever 21 will be so moved as to raise the lever 16, and thereby permit the plunger 12 to be raised from its seat. The valve-seat member 2 of the valve-casing is connected with any suitable inlet-supply of water or 10 other liquid under pressure. As soon as the pressure is relieved from the upper end of the valve-plunger by the descent of the float 24 the pressure of the liquid in the inlet-pipe will force the valve-plunger from its seat 7 15 and the flow into the nozzle member of said valve and thence into the tank. As the water fills the tank the float 24 will be gradually raised, and the lever 16 will thereby be forced downwardly against the valve-plunger 12. 20 This will operate to force the valve against the seat 7, and so finally completely close the inlet for shutting off the flow of water or other liquid. The arrangement of parts is such that the float will have a free powerful lever- 25 age upon the valve-plunger for forcing it against its seat. It will be further seen that the plunger of the valve can be taken out of the casing without disturbing the nozzle member or the valve-seat member by merely un- 30 screwing the cap 8. The nozzle-casing can also be removed from the valve-seat member without disturbing the latter or having to disconnect the same from the inlet-pipe. This makes an extremely convenient construction 35 for repairing or inspecting a valve, and such a valve can be kept in order with very little difficulty.

While I have herein illustrated and described my preferred form of mechanism, it 40 will of course be understood that there can be numerous modifications as to minor details and the relative arrangement of the parts without departing from any of the essential features of the invention or sacrificing any 45 of the advantages thereof. For instance, instead of constructing the valve-seat portion 2 and the nozzle portion 1 of two separate parts and securing the same together for the purpose of connecting them as I have shown 50 I may, if desired, form the two portions in one piece or casting. This and many other minor changes of a like nature may be made, all of which I regard as coming within the scope of my invention.

Having now described my invention, what I claim as new, and desire to secure by Letters Patent, is—

1. A tank-valve, comprising a casing formed

with an interior valve-seat, a plunger adapted to move longitudinally within said casing, 60 a valve upon the inner end of said plunger designed to engage said valve-seat, the upper end of said plunger projecting beyond said casing and slotted transversely, a standard projecting from said casing, a lever fulcrummed 65 to said standard and extending through the slot in said plunger, a relatively long slotted standard projecting from the opposite side of said casing to that of the first-mentioned standard and to a point above the parallel 70 plane of the top of said plunger, the free end of said lever being passed through the slot of said slotted standard and guided thereby, a float-lever pivoted to the upper end of said slotted standard, above said plunger-operating lever and extending parallel thereto transversely across the upper end of said plunger and means pivotally securing one 75 end of said float-lever to the free end of said first-mentioned lever, projecting beyond the 80 said slotted standard, the construction and arrangement being such that a lowering of the float-lever will raise the plunger, by means of its lever, the upward movement of said plunger being limited by contact with 85 said float-lever, substantially as described.

2. In a valve for tanks, the combination of a suitable casing having a valve-seat formed therein, a cap for said casing provided with a vertical bore, a vertically-slidable plunger 90 in said bore, adapted at its lower end to engage said valve-seat and provided at its upper end with a transverse slot, a relatively long radially-extending fulcrum-standard formed on the side of said cap, and extending above the horizontal plane of the top of said cap, a shorter standard formed on said cap opposite the relatively long standard, its top portion lying in the same horizontal plane as the slot in the plunger, a lever pivoted to 100 the shorter standard and extending transversely through the slot of the plunger to a point beyond the extended standard, the portion of such lever in said slot being broadened to fit snugly therein, a float-lever pivoted intermediate its ends to the extended fulcrum-standard and lying transversely 105 above the plunger, and a link connecting the short end of the float-lever with the free end of the plunger-lever.

In testimony whereof I hereunto affix my signature in presence of two witnesses.

JOHN HENRY KOCH.
